Inventor,

James Hewson.

UNITED STATES PATENT OFFICE.

JAMES HEWSON, OF NEWARK, NEW JERSEY.

FASTENING FOR PORTE-MONNAIES AND POCKET-BOOKS.

Specification of Letters Patent No. 14,867, dated May 13, 1856.

To all whom it may concern:

Be it known that I, JAMES HEWSON, of Newark city, in the county of Essex and State of New Jersey, have invented a new 5 and useful improvement in the construction of porte-monnaie and pocket-book frames by the combination of a spring-catch and rings for the purpose of preventing the extraction of porte-monnaies, pocket-books, 10 and purses from the pocket without alarming the owner; and I hereby declare the following to be a full, clear, and exact description of the same, reference being had to the accompanying drawings, which are lettered 15 to correspond with and form a part of this specification.

Description.—The nature of my invention consists in the construction of a catch, or hook, and a spring, either round, spiral, or 20 flat, as shown at (A), Figure 1, that is fastened to the outside of the frame of the porte-monnaie and the catch (b) may be attached to the frame by rivets or otherwise; or a projection may be left upon the edge of 25 the frame for the purpose of forming the catch, or hook, by simply turning it up. The spring is moved or operated by the pressure of the finger upon the knob (c), Fig. 2. (d,) represents a ring that is fastened to 30 the bottom of the pocket by means of a split ring and button or otherwise. This ring (d,) is hooked in the catch (b,) and holds the pocket book or porte-monnaie fast to the pocket, unless the hand is forced down to the 35 bottom, in order to press upon the spring;

and thus detach the porte-monnaie from the ring (d,) which remains fast to the pocket ready to hook into the catch (b,) when required.

Fig. 3, letter (e), represents another kind 40 of catch wherein I have substituted a swivel in place of the ring, the spring is the same and the catch is not used.

I do not pretend to be the inventor of 45 springs, catches, and rings; neither do I claim to be the first one that has applied them to pocket books or porte-monnaie, but the combined application of the spring, catch, and rings, to prevent the extraction 50 of our pocket books by dishonest hands or otherwise, I believe is new, novel, and useful. The bottom of the pocket should be attached to the garment.

Therefore what I claim and desire to secure by Letters Patent of the United States 55 is—

The combination of the catch (b,) Fig. 1, or swivel (e), Figs. 1 and 3, and the spring (A,) with the ring (d,) Fig. 1, attached to the porte-monnaie or pocket book frame, in 60 the manner and for the purpose substantially as described.

In testimony whereof I hereunto subscribe my name in the presence of two witnesses.

JAMES HEWSON.

Witnesses:

D. W. BATEMAN,
